US0D1003440S

(12) United States Design Patent (10) Patent No.: US D1,003,440 S
(45) Date of Patent: * Oct. 31, 2023

(54) WAX WARMER

(71) Applicant: Guangzhou Daydream Cosmetics Co., Ltd., Guangdong (CN)

(72) Inventor: Guolin Li, Guangdong (CN)

() Term: 15 Years

(21) Appl. No.: 29/888,566

(22) Filed: Apr. 2, 2023

(51) LOC (14) Cl. 24-01

(52) U.S. Cl.

CLAIM

The ornamental design for a wax warmer, as shown and described.

DESCRIPTION

FIG. 1 is a front, top and right perspective view of a wax warmer showing my new design;

FIG. 2 is a rear, bottom and left perspective view thereof;

FIG. 3 is a right view thereof;

FIG. 4 is a left view thereof;

FIG. 5 is a front view thereof;

FIG. 6 is a rear view thereof;

FIG. 7 is a top view thereof;

FIG. 8 is a bottom view thereof; and,

FIG. 9 is a front, top, and right perspective view with the lid removed for ease of illustration.

The broken lines illustrate portions of the wax warmer that form no part of the claimed design.
